UNITED STATES PATENT OFFICE.

WALTER DE VILLE, OF EAST LIVERPOOL, OHIO, ASSIGNOR TO THE PALM BROTHERS COMPANY, OF NEW YORK, N. Y.

DESIGN FOR A PLATE OR SIMILAR ARTICLE.

49,256.

Specification for Design.

Patented June 27, 1916.

Application filed May 3, 1916. Serial No. 95,271. Term of patent 3½ years.

To all whom it may concern:

Be it known that I, WALTER DE VILLE, a citizen of the United States, residing at East Liverpool, in the county of Columbiana and State of Ohio, have invented a new, original, and ornamental Design for a Plate or Similar Article, of which the following is a specification, reference being had to the accompanying drawing, forming part thereof.

The figure is a plan view of a plate showing my new design.

I claim:

The ornamental design for a plate or similar article, as shown.

WALTER DE VILLE.

Witnesses:

C. F. BRINDLEY,
A. J. KEDDIE.
